UNITED STATES PATENT OFFICE

CHARLES L. KUBISTA, OF LE SUEUR, MINNESOTA

INK FOUNTAIN OR DIP WELL

Application filed March 12, 1932. Serial No. 598,419.

This invention relates to ink receptacles and the like, and more particularly to dip wells or pits adapted to be associated with conventional ink bottles now in use.

5 It is an object of my present invention to provide an improved ink receptacle of the barometric feed type, by means of which fountain pens may be filled and other pens may be dipped without submerging the pen 10 point too deeply into the fluid or soiling the holder in any manner during the filling or dipping of the same.

It is a further object to provide an extremely simple and efficient dip well which 15 may be associated with conventional types of ink bottles or containers, and which, when so associated, will insure the application of ink to the pen point at a uniform height regardless of the depth of ink within the container, which will minimize the evaporation 20 of the ink when the container is left uncorked, and which will further act as a stopper for the container when the same is sold and from the time it is first used until the 25 contents have been depleted.

More specifically, it is an object to provide in an ink container structure, an inexpensive dip well which will have a frangible lower end, which has a sealing flange or means at its upper end for tight connection with the neck of an ink bottle, and which, when associated with an ink well either by the manufacturer or by the user, may be utilized to form a stopper for the receptacle and after 30 the frangible lower end is broken to produce a barometric feed within the well.

These and other objects and advantages of the invention will be more fully set forth 35 in the following description made in connection with the accompanying drawing, in which like reference characters refer to similar parts throughout the several views, and in which:—

40 Fig. 1 is a side elevation showing a conventional type of ink bottle with an embodiment of my invention associated therewith;

45 Fig. 2 is a vertical section taken substantially on the line 2—2 of Fig. 1, showing a pen disposed in the dip-well;

Fig. 3 is a longitudinal section through one form of the dip-well wherein the lower end of the well is slit in intersecting lines and a frangible jacket or cap is applied to the lower end thereof; 55

Fig. 4 is a cross section taken on the line 4—4 of Fig. 3, looking in the direction of the arrows;

Fig. 5 is a perspective view of a somewhat different form of dip-well, and 60

Fig. 6 is a vertical longitudinal section of the lower portion of the form shown in Fig. 5.

Referring to the drawing, particularly to Figs. 1 to 4 inclusive, a conventional type of 65 bottle or ink container C is shown having the reduced neck or throat 7.

A dip-well 8 depends into the container through throat 7 and as shown in Fig. 1 to 4, is of general frusto-conical shape, having 70 an out-turned supporting sealing flange 8a at the upper and larger end thereof. The well is preferably constructed of somewhat compressible elastic material, such as soft rubber, and the wall or thickness of the material at the lower end of the dip-well is diminished considerably in thickness to afford greater flexibility. The lower end or tip of the dip-well 8 is slit along a series of cross lines which intersect at the longitudinal axis of the well, forming flexible and resilient flaps 8c which substantially close the lower end of the well. If desired, before slitting the lower end of the well, a small axial aperture 8d may be formed through said end. 75

The slit and apertured lower end of well 8 in the form shown in Figs. 1 to 4, is covered by a frangible jacket or cap 9 which may be constructed of any suitable material, such as thin rubber of the nature used in toy balloons. 80 The jacket 9 may be vulcanized or otherwise secured to the lower portion of well 8 to form an air-tight joint. 90

The well 8, with the jacket unbroken, is thrust into the throat of the bottle, and the tip or lower end of the well is submerged considerably below the surface of the normal contents of the bottle and the well is supported by the sealing flange 8a from the edge 95 of the bottle neck. A screw cap 10, having 100

threaded engagement with the exterior of the neck 7 of the container C, has an aperture 10a in the top thereof, said aperture being concentric with the inner periphery of the well 8. Said screw cap clamps the flange 8a tightly against the upper edge of the bottle neck 7, thereby forming a sealed joint.

When inserted in the bottle, as described above, the well constitutes a stopper until such time as the frangible jacket 9 is broken, and hence the bottle, filled with ink or other liquid, may be commercially sold with the well operatively applied.

In use, a pen is thrust downwardly into the well 7, said pen being centered by the conical periphery of said well. The point of the pen easily penetrates the axial aperture 8d and breaks the frangible jacket 9. The jacket, before being punctured, is preferably somewhat stretched and, when punctured, leaves the flaps 8c of the well substantially unrestricted. The height of the lower end of well 8 above the bottom of container C determines the maximum depth to which the pen point is immersed. Since the flange 8a of the well 8 is sealed against the upper edge of the neck of the container, an ink receptacle of the barometric feed type is provided when the jacket or seal at the lower end of the well is broken. Ink will not rise in dip-well 8, and substantially the entire contents of the container may be consumed without danger of dipping the pen point too deeply or soiling the pen holder. The flaps 8c at the lower end of the well will act to yieldably cushion the impact of the pen as it is thrust in the well and will have a slight wiping action against the pen point, preventing an excess of fluid from accumulating on the point.

In Figs. 5 and 6, I show a somewhat different form of dip-well than that previously described. The well indicated by the numeral 12 is of the general shape and structure of the form first described, and preferably is constructed of compressible elastic material, such as soft rubber, the thickness of the material being diminished considerably at the lower and closed end thereof. The closed end of dip-well 12 is not slit or apertured, but, in the forming of the well, grooves 12b are cast or otherwise formed into the material, said grooves penetrating the greater portion of the thickness of the lower end of the well and intersecting substantially at the longitudinal axis of the well.

In this form, the flange 12a of the well is clamped to the upper edge of the neck 7 of the ink receptacle by the screw cap 10, thus forming a tight seal. The well acts as a stopper for the contents of the receptacle until the lower end of the well 12 is punctured. When the user forcibly thrusts a pen into the well, the lower end of the well will be severed along the defined lines of cleavage formed by the grooves 12b, thus permitting

penetration of the pen point into the contents of the receptacle below well 12. After two or three successive uses, the lower end of well 12 will be cut along the several grooves 12b defining flaps 12c which are the equivalent of the flaps 8c of the form first described. 70

It will be apparent that my structure may be incorporated in the ink receptacle by the manufacturer, acting as a closure or stopper, or, if desired, may be sold as an attachment or accessory for conventional types of ink containers now in extensive use. When used as an accessory, it may be removed and operatively positioned in a filled receptacle by closing the open upper end of the well 8 with a cork, or with the thumb, inserting the well in the filled container and sealing the flange 8a. When the cork or thumb is removed, a receptacle of the barometric feed type will have been formed. 80

It will, of course, be understood that various changes may be made in the form, details, proportions and arrangement of the parts, without departing from the scope of my invention, which, generally stated, consists in a device capable of carrying out the objects above set forth and in the novel parts and combinations of parts disclosed and defined in the appended claims. 90

What is claimed is:— 95

1. In combination with an ink container, a well formed integrally from compressible material, the upper end of said well being open and sealed about its periphery to the upper portion of said container, the lower end of said well being spaced above the bottom of the container substantially the distance to which it is ordinarily desirable to dip a pen and being provided with intersecting grooves extending partly through the material, said grooves being adapted to form slits defining flexible flaps when breakage has been effected therealong. 100

2. In combination with an ink container having an externally screw threaded neck, a well formed integrally of flexible and compressible material, the upper end of said well being open and provided with an outwardly extending flange, a screw cap adapted to fit the externally screw threaded neck of said container, the upper portion of said cap being apertured to leave an inwardly extending flange, the flange of said well being adapted to be clamped between the flange of said cap and the upper edge of the neck of said container to secure and seal said well to said container, the lower end of said well being spaced above the bottom of said container substantially the distance to which it is ordinarily desirable to dip a pen and being provided with intersecting grooves extending partly through the material, said grooves being adapted to form slits defining flexible flaps when breakage has been effected therealong. 110

120

125

130

3. In combination with an ink container, an integral well formed of compressible material, the upper end of said well being open and sealed about its periphery to the upper 5 portion of said container, the lower end of said well being provided with intersecting slits defining flexible flaps, and a frangible jacket formed of a sheet of thin elastic material stretched over said lower end to cover 10 said slits.

In testimony whereof I affix my signature.
CHARLES L. KUBISTA.
